UNITED STATES PATENT OFFICE

ARTHUR VON FRANKENBERG, OF NEW YORK, N. Y., ASSIGNOR TO FRANKART, INC.,
OF NEW YORK, N. Y., A CORPORATION OF NEW YORK

DESIGN FOR AN AQUARIUM OR SIMILAR ARTICLE

Application filed August 20, 1929. Serial No. 32,457. Term of patent 7 years.

To all whom it may concern:

Be it known that ARTHUR VON FRANKENBERG, citizen of the United States and resident of New York city, in the county of New York and State of New York, has invented a new, original, and ornamental Design for an Aquarium or Similar Article, of which the following is a specification, reference being had to the accompanying drawing, forming part thereof, in which the figure is a perspective view of an aquarium embodying my new design.

I claim:

The ornamental design for an aquarium or similar article substantially as shown.

Dated August 14, 1929.

ARTHUR VON FRANKENBERG.
